his Attorney.

UNITED STATES PATENT OFFICE.

DANIEL HANDELAN, OF ABERDEEN, SOUTH DAKOTA.

HOT-AIR HEATING SYSTEM.

1,336,901.

Specification of Letters Patent. Patented Apr. 13, 1920.

Application filed October 31, 1917. Serial No. 199,553.

To all whom it may concern:

Be it known that I, DANIEL HANDELAN, a citizen of the United States, residing at Aberdeen, in the county of Brown and State 5 of South Dakota, have invented certain new and useful Improvements in Hot-Air Heating Systems, of which the following is a specification.

My invention relates to hot air heating systems and has for its object to provide a compact and novel arrangement of hot-air conduits such that the body of hot air will travel the greatest available distance vertically, being discharged through laterals at the top of the room, preferably downwardly through the ceiling. This arrangement of hot-air delivery pipes is combined with a system of withdrawal pipes of relatively large size located adjacent the floors 15 of the rooms. By this means the air in the house is caused rapidly to circulate through the rooms and a furnace chamber and back through the delivery conduits and into the rooms. This rapid circulation insures a 20 withdrawal of the largest amount of heat from the radiation surface of the furnace walls so that these surfaces are kept relatively cool and the air is delivered to the rooms at a moderate temperature, even with 25 a very hot fire, the heating effect being brought about by rapid circulation of the air rather than the discharge of very hot air into the room with its injurious effect upon the furniture and the occupants.

The full objects and advantages of my invention will appear in connection with the detailed description thereof and are particularly pointed out in the claims.

In the drawings, illustrating the application of my invention in one form,—

The single figure represents a cross-sectional view of a dwelling house showing the arrangement in reference to floors of the delivery and return pipes of my system.

As illustrated, the outside walls 10 of a house have between them supported in the usual way a basement floor 11, a first floor 12, second floor 13, and an attic floor 14, above which is the roof 15. A chimney 16 45 extends from the basement through the several floors and the roof, preferably at a central part of the house. Located adjacent the chimney in the central part of the basement is a hot-air furnace 17 of usual 50 construction which communicates with the chimney 16 through a smoke-pipe 18. Ex-

tending from the top center of the air-chamber of the furnace 17 is a central delivery pipe 19 which passes through the first floor 12, the second floor 13 and the attic 60 floor 14 in a vertical line. Pipe 19 is contracted at 20, where it passes through the second floor 13, at which point laterals 21, 22, 23 extend along the floor between the joists, discharging downwardly at the ceiling of the first-floor rooms through registers 24, 25, 26 controlled by dampers 27 which are operated by suitable chains 28. Other laterals 29, 30 and 31 extend from the diminished upper end of the central pipe 70 19. As shown, these laterals are above the attic floor and discharge downwardly through said floor and the ceiling of the second-story rooms by branches 32, 33 and 34 controlled by dampers 35 which are operative by suitable chains 36. A central damper 37 at the upper end of the vertical pipe 19 is controlled by chain 38 and is adapted to be operated so that more or less 75 hot air may be diverted into either of the 80 pipes 29 or 30 according to the side of the building subject to wind pressure.

From this arrangement it will be seen that hot air from the furnace 17 passes directly upward from the hot-air chamber 85 to the highest possible point for delivery to both the first floor and the second floor. This results in a high velocity of air travel which is not materially diminished by the short travel through the laterals, since these 90 laterals everywhere, for a given floor, are in the same plane and may be made relatively short. Return-pipes 40, 41 connect with the lower part of the hot-air chamber and the furnace 17 and communicate through laterals 42 and 43 with vertical return-pipes 44, 45, 46 and 47 located near the outside 100 walls of the house, and preferably within or adjacent central partition walls. Return-floor registers 48 and 49 communicate with the pipes 45 and 47 at the floor of the second-story rooms, and similar return-floor registers 50 and 51 communicate with the pipes 44 and 46 at the floor level of the first floor. A fresh air-pipe 52 controlled by a 105 damper 53 communicates at 54 with the lateral 43 so as to permit fresh air to be introduced into the furnace chamber as desired.

The return pipes, it will be noted, are of relatively large size, as are the registers 110 opening into them, thus permitting free and rapid travel of the return-air to the

hot-air chamber of the furnace. By this means, in combination with the central delivery pipe and its lateral discharge at the highest point possible of the rooms of any 5 floor, the air is caused to circulate through the rooms with very great rapidity, thus taking heat from the radiating members of the furnace with corresponding rapidity and warming the rooms of the house without 10 the use of very hot air.

I claim:

1. A hot air heating system for buildings comprising a centrally located furnace and hot air chamber therein, a vertical delivery pipe extending from said hot air chamber through all of the floors and ceilings of the building to be heated, laterally extended discharge pipes leading from said vertical pipe, the outer ends of said lateral pipes 15 being turned downwardly through the ceilings to deliver hot air at the highest point in the rooms, and return flow pipes of relatively large size having withdrawal open- 20

ings located at the floors of the various rooms, said withdrawal pipes being positioned adjacent the outside walls of the building. 25

2. A hot-air heating system for buildings comprising a furnace located at the lower central point of the building, a vertical delivery pipe extending directly upward from the furnace through all of the floors and ceilings of the building, said pipe being reduced in size above intermediate floors, discharge pipes leading from said vertical 30 pipe immediately above the ceilings of the rooms, the outer ends of said lateral pipes being turned downwardly through the ceilings and flush therewith to deliver hot air at the highest point in the rooms, and return 35 flow pipes leading from withdrawal openings located at the floors of the various rooms. 40

In testimony whereof I hereunto affix my signature.

DANIEL HANDELAN.
